PATRICK V. DUNN, OF CALAMUS, WISCONSIN.

Letters Patent No. 88,856, dated April 13, 1869; antedated April 5, 1869.

IMPROVEMENT IN DEVICE FOR HOLDING EDGE-TOOLS WHILE BEING GROUNDED.

The Schedule referred to in these Letters Patent and making part of the same.

To all whom it may concern:

Be it known that I, PATRICK V. DUNN, of Calamus, in the county of Dodge, and State of Wisconsin, have invented a new and useful Improvement in Device for Holding Edged Tools, Gun-Barrels, Rods, or other articles upon Grindstones or Emery-Wheels, while in the Process of being Ground or Polished; and I do hereby declare that the following is a full, clear, and exact description of the construction and operation of the same, reference being had to the annexed drawing, making a part of this specification, in which the drawing is a perspective view of my invention, showing the method of using the same.

This invention consists of an oblong frame, of any suitable material, of sufficient length and width for the stone or wheel to play, over which the device is to be used.

From the ends of this frame, handles are extended, for the purpose of guiding or operating the same.

To the sides of the frame are attached adjustable standards, which may be raised or lowered, placed back or forward of the stone, and secured in place by thumb-screws.

On the top of the standard is a revolving head, from which an arm extends on either side.

Upon these arms rollers may be adjusted according to the size or thickness of the article being polished or ground, the article being held upon the stone by means of this arm, between which and the stone the article

being ground is moved either rapidly or slowly, in proportion as the rollers are set obliquely to the stone.

In the accompanying drawing similar letters of reference indicate corresponding letters in the specification.

A A represent a grindstone.

B, the bench or table on which the stone is hung.

c c represent a frame over the stone, in which to

operate my invention.

To enable others skilled in the art to make and use my invention, I will proceed to describe its construction.

a a a represent the frame.

b b, the handles of the frame.

c c represent the adjustable standard.

d d d, the thumb-screws.

e e e e, the head and adjustable arms.

F F represent the rollers; and

g g represent the knife in process of grinding.

What I claim, and wish to secure by Letters Patent,

is—

The combination and arrangement of the frame a a, the handles b b, the adjustable standard c c, the thumb-screws d d d, the adjustable head and arms e e, the rollers F F, substantially as described, for the purposes specified.
